MOTION PICTURE CAMERA

Norman R. Kubnick, Skokie, Ill., assignor to Bell & Howell Company, Chicago, Ill., a corporation of Illinois

Filed Dec. 2, 1964, Ser. No. 82,875

Term of patent 14 years

(Cl. D61—1)

FIG. 1 is a perspective view of a motion picture camera showing my new design;

FIG. 2 is a perspective view of the opposite side thereof, and

FIG. 3 is a rear elevational view thereof.

The bottom of the motion picture camera is substantially plain and unornamented.

I claim:

The ornamental design for a motion picture camera, as shown and described.
